(57) **CLAIM**

The ornamental design for a computer keyboard, as shown and described.

DESCRIPTION

FIG. 1 is right, front isometric view thereof;
FIG. 2 is a left, bottom isometric view thereof;
FIG. 3 is a top plan view thereof;
FIG. 4 is a bottom plan view thereof;
FIG. 5 is a front elevational view thereof;
FIG. 6 is a rear elevational view thereof;
FIG. 7 is a left elevational view thereof;
FIG. 8 is a right elevational view thereof;
FIG. 9 is a right, front isometric view of a second embodiment of a computer keyboard showing our new design;
FIG. 10 is a left, bottom isometric view of the second embodiment;
FIG. 11 is a top plan view of the second embodiment;
FIG. 12 is a bottom plan view of the second embodiment;
FIG. 13 is a front elevational view of the second embodiment;
FIG. 14 is a rear elevational view of the second embodiment;
FIG. 15 is a left elevational view of the second embodiment; and,
FIG. 16 is a right elevational view of the second embodiment.

The broken lines are shown in the views for illustrative purposes only and form no part of the claimed design.

In FIGS. 9-16 the areas including stipple shading have a different contrasting color as compared to the areas that do not include stipple shading.
